UNITED STATES PATENT OFFICE.

NEAL TANQUARY, OF LOS ANGELES, CALIFORNIA.

DESIGN FOR A RADIATOR-CAP ORNAMENT.

Application filed April 16, 1927. Serial No. 21,627. Term of patent 3½ years.

To all whom it may concern:

Be it known that I, NEAL TANQUARY, a citizen of the United States, residing at Los Angeles, in the county of Los Angeles and State of California, have invented a new, original, and ornamental Design for Radiator-Cap Ornaments, of which the following is a specification, reference being had to the accompanying drawing, forming a part thereof.

Fig. 1 is a side elevational view of a radiator cap ornament showing my new design.

Fig. 2 is a plan view of the ornament.

I claim:

The ornamental design for a radiator cap ornament, as shown.

NEAL TANQUARY.
